UNITED STATES PATENT OFFICE.

KARL AUGUST BRÄUNING, OF HERSTAL, BELGIUM.

AUTOMATIC FIREARM.

1,411,473.

Specification of Letters Patent. Patented Apr. 4, 1922.

Application filed September 26, 1917. Serial No. 193,305.

(GRANTED UNDER THE PROVISIONS OF THE ACT OF MARCH 3, 1921, 41 STAT. L., 1313.)

To all whom it may concern:

Be it known that I, KARL AUGUST BRÄUNING, engineer, a subject of the Emperor of Germany, residing at Herstal, Belgium, have 5 invented certain new and useful Improvements in Automatic Firearms (for which I have filed an application in Germany July 2, 1914;) and I do hereby declare the following to be a full, clear, and exact description of the invention, such as will enable other skilled in the art to which it appertains to make and use the same, reference being had to the accompanying drawings, and to letters or figures of reference marked there- 10 in, which form a part of this specification.

The present invention has for its object a device by means of which it is possible to perform, with an automatic firearm, a semi-automatic fire, that is to say, a fire during 15 which several operations are performed by hand, in order to diminish the rapidity of the fire without however imposing upon the shooter fatiguing efforts.

In the known semi-automatic fire arms use 20 is made of a device for retaining the breech bolt in open position after each shot in such manner that it is necessary, when continuing the fire, to actuate said device so as to free the breech bolt, which consequently closes 25 under the action of the recoil spring.

The inconvenience of these devices is that the fire is not rendered sufficiently slow.

In the device according to the present invention, the operations which require 30 strength, such as unbolting and opening the arm, extracting and ejecting the shell, are performed automatically, while the shooter is obliged to accomplish by the hand as in non-automatic firearms, the closing and locking 35 of the breech bolt and also, in certain cases, the introduction of the cartridge at each shot.

These results are obtained by means of a device which renders it possible to lock the 40 recoil spring in such a position that it acts no more upon the movements of the bolt except as a buffer. For this purpose the recoil spring, on being compressed, can be locked and disconnected from the bolt, which 45 remains capable of moving freely.

The compressed spring may also serve as a

buffer in order to limit the recoil of the breech bolt.

The accompanying drawings show by way of example a preferred embodiment of the 55 invention.

Fig. 1 is a side view, partially in section, of a firearm provided with the device for the semi-automatic fire.

Figs. 2 and 3 show respectively a top view 60 and a side view of the device on an enlarged scale.

Figs. 4 and 5 are sections taken on A—B in Fig. 3, showing the parts in two different positions.

Fig. 6 is a section on C—D of Fig. 5.

Fig. 7 as a view of a part shown separately.

Fig. 8 is a partial side view showing 70 several interior parts of the device.

The firearm comprises a breech-bolt 1 sliding in the hollow of the breech-frame 2 and receiving the action of a recoil spring. The latter is in the form of a helical spring 3 resting at its rear end against the bottom of 75 a hollow cap 4 closing the breech frame and at the other end against the brim 5 of the socket 6. The latter is put on a cylindrical extension 7 of the breech bolt without being secured to said extension.

According to the present invention, when semi-automatic firing is to be performed, it is only necessary to attach the socket 6 to cap 4, at the moment the spring is compressed. After this has been done, the 85 breech bolt is yet capable of moving in the breech frame, whilst the extension 7 can slide freely out of the socket 6.

Accordingly, the socket 6 is provided with a head 8 which, when the breech bolt has 90 reached the rear end of its travel, passes through a circular opening provided in the bottom of the hollow cap 4. Behind said opening is slidably mounted a little arresting or locking member 9, also provided with 95 a circular opening 12, which can occupy two positions. The position shown in Fig. 4 corresponds to the automatic fire, the head 8 and its enlarged portion 11 are then allowed to pass freely through the openings 10 and 100 12 which are exactly the one behind the other. When on the contrary the member 9

is in the position shown in Fig. 5, the edge 13 of the opening 12 prevents the enlarged portion 11 from getting out and the recoil spring 3 is consequently locked.

5 The arresting or locking member 9 is displaced by means of the cover 14 secured at the rear end of the cap 4. The inner face of the bottom of this cover is shown in Fig. 7; it is provided with a hollow 15, the edges 10 18 of which are intended to work as cams and act upon the rounded portion 16 of the arresting member 9 when the cover 14 is caused to turn on the cap 4. The member 9 is guided during its sliding movements by 15 its ribs 27 which are engaged in corresponding grooves of the bottom of the cap 4. A little spring 17 urges always the arresting member 9 towards the position of semi-automatic fire when such a movement is rendered possible according to the position of the cam 18 (Figs. 5 and 6).

When the cover 14 is then caused to turn through an angle of about 90°, the portion 19 of cam 18 is brought into contact with 25 the rounded portion 16 of member 9 and urges said member 9 again in the position corresponding to the automatic fire (Fig. 4). A button 20 associated with spring 17 and passing through the slit 21 of the cover, is 30 used in order to lock the cover in the one or the other position; this button is provided with a lateral projection 22 which enters into the notches 23 and 24 of the slit 21. It is to be noted that the edge of 35 the opening 12 is provided with an inclined or bevelled surface 25 in such a manner that if the arresting member 9 is brought into the position for the semi-automatic fire when the breech is closed, at the following recoil 40 movement of the breech bolt the portion 11 of the head 8 urges the arresting member 9 sideways so as to enter into the opening 12, after which it is seized by the edge of said opening that comes again in its former position under the action of the spring 7.

It is accordingly always possible to make the arm ready for semi-automatic fire or to make it ready for automatic fire whatever 50 may be the position of the breech bolt. The purpose of using a cam 18 in order to move the arresting member 9 is to render this movement more easy when the recoil spring is compressed.

When the recoil spring is compressed for 55 the semi-automatic fire, it can serve as a buffer in order to damp the impact of the breech bolt against the socket 6. In the embodiment shown, the breech bolt is closed by the hand by means of a cover, not shown, 60 that slides on the breech frame and is provided with inner projections which pass through slits 26 in the breech frame so as to come in engagement with the breech bolt.

The cap 4 is secured to the breech frame

by any suitable means, such as a bayonet- 65 device.

What I claim is:

1. In a fire arm, a breech frame, a breech bolt, a socket embracing the rear end of said breech bolt, a helical spring embracing 70 said socket and resting against the rear end of said breech frame, a movable cover at the rear of said breech frame, and means actuated by said cover adapted to arrest and lock the socket to the frame when the spring 75 is compressed so that the bolt may operate independently of said spring.

2. In a fire arm, a breech frame, a breech bolt, a socket embracing the rear end of said breech bolt, a helical spring embracing said 80 socket and resting against the rear end of said breech frame, an angularly displaceable cover at the rear of the breech frame, and means actuated by said cover adapted to arrest and lock the socket to the frame when 85 the spring is compressed, so that the bolt may operate independently of said spring.

3. In a fire arm, a breech frame, a breech bolt, a socket embracing the rear end of said breech bolt, a helical spring embracing said 90 socket and resting against the rear end of said breech frame, a locking member for said socket, and a movable cover arranged at the rear of the breech frame and provided with inner cam surfaces adapted to engage 95 the said locking member so as to move the same into position for arresting and locking the socket when the spring is compressed.

4. In a fire arm, a breech frame, a breech bolt, a socket embracing the rear end of 100 said breech bolt, a helical spring embracing said socket and resting against the rear end of said breech frame, a locking member having a bevelled portion which permits of the spring and socket being automatically locked 105 by the recoil, and a movable cover arranged at the rear of the breech frame and provided with inner cam surfaces adapted to engage the said locking member so as to move the same into position for arresting and locking the socket when the spring is compressed.

5. In an automatic firearm, a breech frame, a sliding breech bolt, a socket embracing the rear end of said breech bolt, a 115 helical recoil spring embracing said socket and resting against the rear end of said breech frame, a sliding locking member for the socket, a movable cover arranged at the rear end of the breech frame and provided 120 with inner cam surfaces adapted to move the locking member into position to lock the socket, and a spring button for locking said movable cover in any adjusted position.

6. In an automatic firearm, a breech 125 frame, a sliding breech bolt, a socket embracing the rear end of said breech bolt, a helical recoil spring embracing said socket

and resting against the rear end of said breech frame, and locking means adapted to arrest and lock the socket when the recoil spring is compressed while permitting 5 of a slight rearward movement of the socket, so that the compressed spring may serve as a buffer for the breech bolt.

In testimony whereof I affix my signature in presence of two witnesses.

KARL AUGUST BRÄUNING.
